UNITED STATES PATENT OFFICE.

THOMAS CRANEY, OF BAY CITY, MICHIGAN.

GRATE.

1,297,293.

Specification of Letters Patent.

Patented Mar. 11, 1919.

Application filed March 16, 1917. Serial No. 155,295.

To all whom it may concern:

Be it known that I, THOMAS CRANEY, a citizen of the United States of America, residing at Bay City, in the county of Bay 5 and State of Michigan, have invented certain new and useful Improvements in Grates, of which the following is a specification.

This invention relates to grates.

10 One object of the invention is to provide a grate for use in furnaces adapted to burn refuse organic matter such as waste wood, saw-dust, garbage and other waste matter.

Another object is the provision of a grate 15 having the maximum amount of air space so that wet wood, refuse, garbage and other wet waste matter can be burned as readily as dry fuel.

With these and other objects in view, the 20 present invention consists in the combination and arrangement of parts hereinafter more fully described, illustrated in the accompanying drawings, and particularly pointed out in the appended claims, it being 25 understood that changes may be made in the form, size, proportion and minor details without departing from the spirit or sacrificing any of the advantages of the invention.

30 In the drawings:—

Figure 1 is a plan view of a furnace provided with my grate.

Fig. 2 is a sectional side elevation of the same.

35 Fig. 3 is a detail of the grate bar.

Fig. 4 is a side elevation thereof.

Fig. 5 is a sectional view of the same.

Fig. 6 is a plan view of the grate bearing bar.

40 Fig. 7 is a side elevation thereof.

Fig. 8 is a sectional view of the same.

Fig. 9 shows the position of the grate bars when assembled.

45 Fig. 10 is a sectional view of the parts shown in Fig. 9 with arrows showing the course of the air, and the area of air space.

In the drawings, 1 indicates an ordinary refuse furnace provided with the door 2 for the removal of ashes, and provided with my 50 improved grate, indicated as a whole by the numeral 3.

The grate 3 consists of a plurality of bearing bars 4 connected together at their inner ends by means of the conical cap member 5. The bearing bars are bolted or otherwise secured to said cap member, and radi-

ate therefrom in a downward direction, the lower ends of said bars being secured in any suitable manner to a plurality of plates 6 secured in the wall of the furnace. Thus a 60 pyramidal shaped grate is formed as clearly shown in Fig. 2.

The bearing bars are reinforced throughout their length by means of the tie-rods 7 and are angular in cross section as shown 65 in Fig. 8. These are stepped throughout their length as shown in Fig. 7 to provide a plurality of bearing faces 9, situated on each side of the apex 8 of each bar. Each bearing face 9 has a notch 10 cut in the edge 70 thereof.

A plurality of grate bars 11 are provided each having a rib 12 extending from the lower side thereof, but terminating short of each end thereof. Extending from the upper 75 sides of the said bars 11 are a plurality of equally spaced lugs 13, extending across the width of the bars.

In assembling my grate the ends of the ribs 12 of the grate bars 11 are received in 80 the oppositely disposed notches 10 of the bearing bars 4 whereby the free ends of each grate bar 11 are supported by the bearing faces 9 of the bearing bar 4. The edge of each grate bar overlaps the adjacent edge 85 of the succeeding bar as shown in Figs. 2 and 10 and by reason of the lugs 13, the said bars are spaced an equal distance from each other. It will be apparent that beginning at the top, each succeeding grate bar 90 is longer than the preceding bar and thereby the lugs 13 which are equally spaced apart are out of alignment on adjacent bars, thus providing a large area of air space between adjacent bars for the circulation of 95 air as shown by the arrows in Figs. 2 and 10. By reason of the ends of the ribs 12 being received in the notches 10 the grate bars 11 are securely held against displacement, while at the same time they can be easily removed. 100

The aforementioned plates 6 located at the lower part of the grate are provided with channels 14 running parallel with the lowermost grate bar 11 and communicating by short channels 15, with a depression or shallow receptacle 16. When burning garbage, the solder running from the grate bars 11 is conducted by means of the channels 14 and 15 into the receptacles 16, where the same can be removed by ladles or piped to 110 any suitable place.

From the foregoing it will be apparent

2
that I have provided a novel grate possessing characteristics that enable it to be easily manufactured, easily assembled and taken apart and one in which plenty of air circulation is provided, which air circulation is very essential in grates used in the burning of wet refuse:

What I claim is:—

1. A pyramidal grate for refuse burning furnaces, comprising a marginal base, a cap member located above the plane of the base, inclined bearing bars secured at their ends to the marginal base and cap member and radiating from the latter and provided at intervals with seats and separate grate bars extending across the spaces between the bearing bars and progressively decreasing in length toward the center of the grate and having their terminals removably arranged upon the said seats.
- 10 2. A pyramidal grate for refuse burning furnaces, comprising a marginal base having an opening and adapted to be mounted in the walls of a furnace, a centrally arranged cap member located above the plane of the marginal base, inclined bearing bars secured at their ends to the base and the cap member and radiating from the latter, said bearing bars having angularly related side portions or wings provided at intervals with spaced seats and separate transversely disposed grate bars having their ends removably arranged on the said seats, said grate bars progressively decreasing in length from the marginal base to the cap member.
- 15 3. A pyramidal grate for refuse burning furnaces, comprising a marginal base having an opening and adapted to be mounted in the walls of a furnace, a centrally arranged cap member located above the plane of the marginal base, inclined bearing bars secured at their ends to the base and the cap member and radiating from the latter and provided at opposite sides with spaced

seats, said seats being provided at the side edges of the bearing bars with notches and separate transversely disposed grate bars extending across the spaces between the bearing bars and having their ends arranged upon the said seats and provided with flanges engaging the notches and detachably interlocking the grate bars with the said seats and holding the grate bars against lateral and longitudinal movement.

4. A pyramidal grate for refuse burning furnaces comprising a marginal base, a conical cap member located above the plane of the base, inclined bearing bars extending from the base to the cap member and radiating therefrom, said bearing bars being provided at their ends and at points intermediate of their ends with lugs located at the under side of the said bearing bars, the end lugs being secured to the marginal base and the cap member, tie rods secured to the end lugs and arranged on the intermediate lugs to form a truss, and separate transversely disposed grate bars removably supported at their ends upon the bearing bars.

5. A pyramidal grate for refuse burning furnaces comprising a base composed of marginal plates connected together at their ends and provided with depressions and having grooves extending inwardly from the depressions, a cap member located above the plane of the said plates, inclined bearing bars radiating from the cap member and secured to the same and to the said plates, and separate transversely disposed grate bars arranged upon the bearing bars and progressively decreasing in length from the marginal plates to the cap member, said grooves terminating below the lowermost grate bars and said depressions being located between the grate bars and the margin of the grate to afford access to the said depressions.

In testimony whereof I affix my signature.
THOMAS CRANEY.

Copies of this patent may be obtained for five cents each, by addressing the "Commissioner of Patents, Washington, D. C."
